Atty.

UNITED STATES PATENT OFFICE

2,661,973

RETAINING MEANS FOR DOORS AND
THE LIKETheodore J. Sweger, Chicago, Ill., assignor to
Illinois Railway Equipment Company, Chicago,
Ill., a corporation of Illinois

Application July 27, 1950, Serial No. 176,091

4 Claims. (Cl. 292—246)

1

My invention relates to means which automatically effects latching or holding engagement with a hingedly mounted member or door to hold it in open position; my improved means being especially adapted for use with refrigerator cars which, in keeping with the Interchange Rules of the American Association of Railroads, must be provided with means whereby the heavy hingedly mounted doors will be latched or held in open position.

My improved means is devised to automatically and positively effect holding relation, under all adverse weather conditions, with the swinging member or hingedly mounted door when the latter is swung to complete open position and which may be easily released from holding condition when desired.

While my improved means is especially designed for use with the heavy horizontally swinging doors of refrigerator cars, it is apparent that the latching means is equally well adapted for other uses as, for example, with attached covers or lids of containers and which at times it is necessary that they be positively held in complete open position.

The objects and advantages of my invention will be readily apparent from the detailed description of the accompanying drawing wherein:

Figure 1 is a perspective view of the holding latch or retainer member.

Figure 2 is a perspective view of the keeper or actuating member.

Figure 3 is a perspective view of both members shown in latching or holding condition.

In the specific exemplification of my invention the latch or retainer member 10, as shown in Figure 1, preferably made of suitable metal, consists of a body portion or bracket 11 with rear flat portions or surfaces to enable it to be immovably secured to the non-movable member or exterior wall of a railroad refrigerator car by suitable fastening means, such as welding or by bolts which pass through proper holes in the back wall of the member.

The ends of the bracket or body portion 11 are bent or formed to extend outwardly at right angles to provide the lobes or ears 12 and 13, and at least one of the ears, for example, ear 13, provided with a lug or lip 14 extending inwardly toward the opposite end 12 and arranged adjacent the lower perimeter of the end 13.

Swingingly mounted between the apertured ends or arms 12, 13 of the bracket member 10 is a single-piece bifurcated latch member pref-

2

erably consisting of a pair of similar cylindrical bars 15, 16 radiating approximately ninety degrees apart from the common axis or trunnions 17, 17 which are rotatably mounted in suitable holes in the two ends or arms 12, 13 of the bracket 10.

The latch member is prevented from complete rotation by the lug 14 which protrudes into the oscillatory path and which holds the bar 15 and bar 16, in initial or proper position, against the action of gravity as indicated in Figure 1, for striking engagement by a keeper or actuating member 18.

The keeper 18 consists of a rigid shank portion 19 of predetermined length with attaching ears 20, 20 at one end and terminating at the other end in a cam-like head and hook 21 provided with an upwardly and somewhat rearwardly sloping or curving surface at 22, which causes the two-bar latch member to swing inwardly and upwardly from the position shown in Figure 1 in advance of the cam-hook 21.

The inward swing of the bar 16 causes bar 15 to swing upwardly and slightly forward of dead center to clear or ride over the top 22 of the cam-hook 21 and to be forced down forward of the latter sufficiently so that when the bar 16 reaches the dwell point of the cam 22 engagement of the bar 15 with the cam-hook has been effected.

With proper stops, such as lug 14, the rotating latch member will always be within a predetermined arc of operation and consequently ensure correct engagement with the cam-hook of the keeper 18.

In order to prevent the too far introduction of the keeper during a forcible swing of the heavy refrigerator car door—or other element to be latched in place—I show the rear wall of the bracket 11 provided with a forwardly presented vertical corrugation or rib 23 with which the cam-hook end of the keeper 18 will engage and prevent reverse or rearward swing of the latch bar 16 while in the raised or vertical position shown in Figure 3. With the latch bar 16 held in the manner mentioned, the bar 15 will be resting on top of the shank of the keeper 18 and in the outward path of the cam-hook 21.

By reason of bar 15 extending forwardly of its pivotal axis of the latch member, bar 15 automatically drops to its latching position shown in Figure 3; while at the same time bar 16 will be maintained in the elevated position where the operator's finger may easily grasp and 55 swing it rearwardly thereby causing the asso-

ciated bar to swing upwardly out of the path of the cam-hook when the door or latched member is to be moved to closed position.

The shank of the keeper 18 should be of a rigid non-flexing nature and when used in connection with the heavy doors of refrigerator cars and subject to more or less rough use, I have shown the keeper composed of two matching sections, arranged back to back and preferably intimately secured together, as by welding, although when possible the keeper may be made of a single piece of sufficiently heavy non-bending stock.

As is apparent from the construction shown, my improved latching means is designed to properly operate under adverse weather conditions and provide positive holding or latching engagement, conditions essential to meet the requirements of the rules of the American Association of Railroads.

What I claim is:

1. Retaining means of the character described comprising a bracket member with laterally spaced forwardly presented apertured lobes, and a horizontally disposed oscillatingly mounted, single-piece latch member provided with trunnions at opposite ends, pivotally mounted in said lobe apertures to swing through an arc of a vertically disposed circle and having a pair of substantially similar parallel spaced bars radially disposed, approximately ninety degrees (90°) apart and a stop lug on a bracket lobe extending inwardly into the swinging path of said bars whereby complete rotation of the latch member is prevented and one of said bars held in substantially horizontal position in the path of an oncoming keeper.

2. In retaining means of the character described, a latch comprising a bracket having a pair of forwardly presented and laterally spaced lobes provided with aligned holes; a single-piece bifurcated latch member provided with trunnions at opposite ends rotatably mounted in the holes of said lobes, the bifurcations consisting of a pair of substantially similar and parallel cylindrical bars radiatingly arranged on the axes of said trunnions and approximately ninety degrees (90°) apart and integral with the trunnions, stop means secured to the bracket lobe forward of the vertical axes of the trunnions and extending into the swinging path of said bars to prevent complete rotation of the latch member and to hold one of said bifurcations forward of the vertical plane of the trunnions and in the path of an oncoming keeper.

3. In retaining means of the character described, a latch composed of an attaching bracket with forwardly presented parallel and apertured ends, one of said ends having an inwardly presented lug arranged forward of and in a plane beneath that of said apertures, and an elongated latch member composed of trunnions at each end and a pair of bars of round cross-section, arranged parallel and integral with each other and with said trunnions, radially arranged approximately ninety degrees apart, whereby said bars will oscillate in the bracket apertures and swing upwardly and forward of the vertical plane of the axes of said trunnions.

4. In retaining means of the character described, a latch composed of a horizontally disposed bracket with forwardly presented substantially parallel apertured ends, and a latch member composed of a pair of integrally connected bars with angularly disposed ends united with each other to form trunnions rotatably mounted in the apertures of the bracket ends, said bars being spaced apart parallel with each other and arranged to automatically swing vertically and thereby move one of the bars into a plane beneath that of the trunnions and into the path of an oncoming keeper while the other bar is swung upwardly through the arc of a circle and caused to drop forwardly into latching position and said first mentioned bar swung upwardly and over the axis of the trunnions into finger-grasping position, and means whereby complete rotation of the bars through a vertical circle is prevented and the bars normally held in the path of an oncoming keeper.

THEODORE J. SWEGER.
